E. D. CHURCH ET AL

PLATEN ACTUATING MECHANISM FOR BRICK MACHINES AND THE LIKE

Filed May 10, 1922

Patented Oct. 5, 1926.

UNITED STATES PATENT OFFICE.

EDGAR D. CHURCH AND FRANK S. LASH, OF SAGINAW, MICHIGAN, ASSIGNEES TO
JACKSON & CHURCH COMPANY, A CORPORATION OF MICHIGAN.

PLATEN-ACTUATING MECHANISM FOR BRICK MACHINES AND THE LIKE.

Application filed May 10, 1922. Serial No. 559,930.

This invention relates to brick machines and the like, as for example, sand lime brick presses of the type having a platen which is revolvable in a step by step movement and plunger adapted to be forced into plunger pockets radially disposed in the platen and containing the material to be pressed.

Revolvable platens of this general type have heretofore been operated by rocking gears or segmental gears which intermittently actuate the platen through suitable pulley and ratchet drives, the rocking or segmental gear being driven by pitman and crank connection to the main shaft of the brick press.

An object of our present improvement is to provide a new type of platen drive mechanism for machines of the general character referred to, the platen drive mechanism being operated by the usual pitman and adapted to attain the objects of our invention.

These objects are, first, to reduce wear on the reciprocating parts and to lessen the cost of repairs and maintenance by reducing wear on the teeth of the gears that drive the platen.

A further object is to improve the accuracy of operation of the machine and make the machine easier running by so constructing the platen drive mechanism as to eliminate the tendency of the working parts to wear in their bearings and become loose or get out of line.

A still further object is, by a new combination and arrangement of parts, to make the machine much stronger without unduly increasing its weight and to so arrange the working parts as to render them easily accessible for removal when replacement becomes necessary.

With the foregoing and certain other objects in view which will appear later in the specification, our invention comprises the devices described and claimed and the equivalents thereof.

In the drawings, Fig. 1 is a part vertical section of the platen mechanism.

Fig. 2 is a fragmentary side view of the oscillating spider and the bevel gear which is driven by the spider.

As is clearly shown in the drawings, 1 indicates the usual revolving platen of a brick press, or any other type of machine having an intermittently revolvable platen. 2 in-

dicates one of the plunger pockets formed 55 in the platen. The details of the mounting of the platen and of the operating plungers are not shown in the drawing, as they do not form part of our present improvement, which consists in the means which will now 60 be described for imparting to the platen 1 intermittent rotating movement which in practice takes place between the successive operations of the plungers in the pockets 2.

In applying our improvement, we provide a 65 bevel gear 3 on the platen 2, this gear being an annular toothed ring bolted or otherwise secured to the rim flange of the platen, preferably on the under side of the flange.

4 is a bevel gear carried by a horizontal 70 shaft 5 and meshing with gear 3.

Alongside of bevel gear 4 and independently revolvable with respect to gear 4 is a spider 6 having the general appearance of a wheel. The spider is carried by shaft 5 75 and is preferably revolvably mounted on the hub of gear 4, as shown in Fig. 1.

A wrist pin 7 is provided on spider 6 and adapted to be connected by a pitman to the main shaft of the press in the usual manner. 80 The pitman is omitted from the drawing for the sake of clearness.

Preferably the spider 6 is actuated by the pitman in a rocking movement through an angle of approximately 90°.

The back-and-forth oscillating movement of the spider 6 is translated into intermittent revolving movement of gear 3 and platen 1 by means of a radially projecting spring pressed latch 8 mounted on spider 90 6 and adapted to releasably engage a stop 9 on gear 4.

In practice we prefer to provide a plurality of such latches, the number of latches 95 corresponding to the part of a complete circle represented by the angle of oscillation of spider 6, that is, if the spider oscillates through an angle of ninety degrees, or a quarter of a circle, there would be four stops 9 on the gear 4 and preferably four 100 latches 8 on spider 6.

In practice, if it is desired to turn the platen 1 through an angle of sixty degrees at each operation, we prefer to make gear 4 of such diameter with respect to the diameter of gear 3 that the proper angle of movement, say, sixty degrees, will be imparted to platen 1 when the spider 6 is 105

moved through its predetermined angle of oscillation, say, ninety degrees. Consequently gear 4 will be moved through an angle of ninety degrees while platen 1 is moving sixty degrees. Therefore, the same teeth on the two gears will not repeatedly come into contact and the wear on the gears will be uniformly distributed and the life of the wearing parts will be prolonged.

- 19 To make the parts accessible and easily removable, we preferably retain the latch 8 on the spider 6 by means of a bearing 10 bolted to the rim of the spider. The latch is normally pressed outward by a compression spring 11, the pressure of which may be adjusted by a bolt 12 in the usual manner.

To preserve the relative alignment of the gear 3, spider 6 and shaft 5 and to prevent wear, we prefer to mount the hub of gear 4 on a bushing 13 and on the outside of the hub 14 of gear 4 and between the hub and the bore of hub 15 spider 6 we provide a second bushing 15, as shown in Fig. 1.

- 25 Annular oil retaining packings 17 and 18 are provided at the two ends of the hub 15 of spider 6.

To hold the latches 8 in alignment, we preferably secure an annular ring 19 to the face of gear 4, the ring being removable to permit access to the latches for purposes of renewal in case of breakage.

By the means above described, we have produced a mechanism adapted to be actuated by the usual reciprocating pitman of a brick press or similar machine and adapted to impart intermittent rotary movement to the platen without undue wear either on the teeth of the platen actuating

gears or upon the operating parts of the 40 platen drive mechanism.

In the event of a latch becoming inoperative any one or all of the remaining latches will still function and the operation of the machine will not be interfered with. 45

The alignment of the drive gears is maintained for a long period of operation by means of the long bearing arrangement of the hubs of the gear and spider on the shaft 5 and wear the rubbing parts is greatly reduced by the employment of the intermediate bushings heretofore described. 50

Having thus described our invention, what we claim and desire to secure by letters Patent is:

1. A platen actuating mechanism including the intermittent grip device comprising a gear having an internal cam on the rim thereof, a liner on the hub of said gear, a spider revolvable on said liner and adapted to back-and-forth oscillating movement and a radially disposed spring-actuated latch carried by said spider and engaging the cam of said gear. 55

2. A platen actuating mechanism for brick machines comprising in combination a gear, a spider coaxial with said gear and revolvably mounted on the hub thereof and adapted to back-and-forth oscillatory movement thereon, a radially disposed spring-pressed latch carried by said spider, a cam on the rim of said gear, said cam adapted to be releasably engaged by said latch, and a stop forming an abrupt face on said cam. 70

In testimony whereof, we affix our signatures. 75
